HUGH J. HEALION, OF NEW YORK, N. Y.

COSTUMER

Application filed April 2, 1930, Serial No. 440,907. Renewed March 30, 1932.

This invention relates to new and useful improvements in clothes supports and has particular reference to those known as costumers.

5 A main object of the invention is to provide a simple, compact and efficient costumer which can be readily expanded to accommodate more articles of clothing than ordinarily.

10 A further object is to provide a simple and efficient costumer which can be readily expanded and closed with ease and dispatch and with the minimum of effort.

15 A still further object is to provide a costumer which will maintain its strength and rigidity even though it is opened and closed many times and will be firm and strong when opened and supporting a maximum number of articles of clothing.

20 A further object is to provide a simple costumer which can be expanded readily and yet which presents the usual appearance when closed and takes up no more than the ordinary amount of room when closed.

25 Further and more specific objects, features, and advantages will more clearly appear from the detailed description given below when taken in connection with the accompanying drawings which form part of the specification and which illustrate the present preferred form of the invention.

30 In its general contemplation, the invention comprises a costumer which is formed of sections which can be separated and which are provided with clothes supporting elements extending between the separated sections and with means to hold the sections in their separated or spaced positions. The sections when disposed close together present the usual appearance of a costumer and the connecting and locking and holding means are then securely and snugly housed within suitable chambers or spaces within the sections. The sections normally abut each other but can be moved apart when a latch is released to permit suitable connecting elements to be stretched therebetween so as to afford additional space on which to support extra clothing when desired. Such a simple compact device is especially useful in small homes and apartments and in offices when

extra company is present or when a conference is going on to take care of the extra coats and hats by means of this device which when not so used takes up no more than the ordinary amount of floor space. 55

The present preferred forms of the invention are illustrated in the drawings of which,

Fig. 1 is an elevation of the costumer;

Fig. 2 is an elevation of the same when expanded; 60

Fig. 3 is a section taken on the line 3—3 of Fig. 2;

Fig. 4 is a section taken on the line 4—4 of Fig. 2;

Fig. 5 is a section taken on the line 5—5 65 of Fig. 3;

Fig. 6 is a section taken on the line 6—6 of Fig. 5;

Fig. 7 is a section taken on the line 7—7 70 of Fig. 2;

Fig. 8 is a section taken on the line 8—8 of Fig. 2;

Fig. 9 is an elevation in part of one section of a modified form of the costumer;

Fig. 10 is a side elevation of a portion of 75 the auxiliary clothes rack when in operative position and of the form shown in Fig. 9;

Fig. 11 is an underneath view of Fig. 10;

Fig. 12 is a section taken on the line 12—12 80 of Fig. 9;

Fig. 13 is a front elevation of part of a modified section;

Fig. 14 is a section taken on the line 14—14 85 of Fig. 13; and,

Fig. 15 is a side view of the joint for one end of the lower connecting member.

In the forms shown in the drawings, the present and most preferred form of the invention comprises what ordinarily looks like and as normally used is the usual costumer as shown in Fig. 1. This device however is formed of two sections A and B which when disposed abutting each other have the appearance of one integral post disposed vertically and provided with the usual hooks 90 for clothes. A latch 11 holds these sections A and B in their normal closed relation.

When these sections A and B are however separated and moved to the positions shown in Fig. 2, then there extends therebetween 100

an upper clothes supporting rack element or bar 12 and a lower connector in the form of a pair of one-way foldable lock or latching levers such as 13 and 14 which can fold up only in the manner shown in Fig. 2, and which when stretched out will hold the lower ends of the sections A and B the proper distance apart.

The upper clothes rack bar which forms an auxiliary clothes support is preferably 10 pivotally connected to the section A in any suitable manner permanently in a groove such as 15 near the top of the section A. The other end of this auxiliary clothes bar 12 is provided with a cross pin 16 and lies within the upper end of a groove 17 in section B. This pin 16 is normally received on hook members such as 18 and 19 on the lower ends of plates 20 and 21 disposed on the face of the section and is held thereon by an overlying spring 20 latch 22. This latch 22 can be forced aside to permit the pin 16 to be moved off the hooks 18 and 19 and allow the end of the bar 12 to slide down in the groove 17 and swing around the pivot of the other end thereof when the sections are drawn close together. Thus the bar 12 will be housed within the groove 17 when the sections are closed.

Preferably the bar 12 is provided with a 30 series of swingable clothes hangers such as 23 which have upturned ends 24 and normally lie in the plane of the bar 12 but can be swung at right angles thereto. The upturned ends when normally disposed lie in cut-away portions on the lower face of the bar 12, as shown in Figs. 5 and 6. They preferably swing in a horizontal plane when the bar is stretched across between the separated sections A and B.

40 Preferably the levers 13 and 14 are joined to brackets such as 25 disposed in the lower ends of the grooves such as 26 in the sections A and B.

As shown in Figs. 5 and 6 the groove 17 45 is closed partly by means of strips such as 27. The lower ends of these strips 27 as shown in Fig. 2 are slightly spaced from the lower end of the groove 17 to permit the pin 16 to be withdrawn from the groove 17 when 50 desired.

As shown in Figs. 9, 10, 11, and 12 the auxiliary bar 12 may have a form of modified hanger such as 28 which moves in a vertical plane to depend from the lower face of the 55 bar 12 when it is stretched across between the sections A and B as shown in Fig. 10. The hangers are in the forms of yoke shaped hooks 29 which at their upper ends are split into spaced portions 30 and 31 to straddle the 60 bar 12. When disposed flat against the bar 12 they lie in cut away portions such as 32 shown in Fig. 10. When the bar 12 in this form is housed in the grooves 15 and 17 these grooves are naturally made somewhat wider 65 than before.

In the operation of the device, the sections A and B are assumed to be in the closed position shown in Fig. 1 and it is desired to expand the costumer to provide room for more than the usual number of coats and hats. The 70 latch 11 is released and the sections pulled apart. When this is done the bar 12 at its free end with the pin 16 in the slot 17 will ride up in the slot until it reaches the hooks 18 and 19. The hand is then applied to lift the pin onto 75 these hooks under the spring 22. The hangers on the bar 12 are then swung into operative position and the locking levers 13 and 14 are then in their fully extended and locked position.

80 Thus there is provided a simple, compact, strong, and efficient device which can be readily and easily operated to afford extra room for coats and hats when desired and which can be closed up to occupy the usual amount 85 of floor space when not in use as an expanded costumer.

While the invention has been described in detail and with respect to a present preferred form thereof, it is not to be limited to such 90 details and forms since many changes may be made and the invention embodied in other forms and modifications without departing from the spirit and scope of the invention in its broadest aspects. Hence it is desired to 95 cover any and all forms and modifications of the invention coming within the language or scope of any one or more of the appended claims.

100 What is claimed, is,

1. A sectional costumer which comprises a pair of sections adapted normally to lie close to each other, means for latching the sections in their closed abutting position, said sections having abutting grooves in their adjacent faces, a cross bar pivoted in the groove in one section and free to slide in the groove of the other section at the end thereof, means to latch the free end of the cross bar in a predetermined position in said groove, and foldable levers disposed in the grooves near the bottom of the grooves to expand when the sections are separated and hold the sections in their separated positions. 105

2. A sectional customer which comprises 110 a grooved section, a bar having an end movable in said groove, a pin on the end of said bar, hooks in said groove to receive and support said pin and spring means disposed near said hooks to hold the pin thereon. 115

Signed at New York city, in the county of New York and State of New York this 31st day of March A. D. 1930.

HUGH J. HEALION.
